UNITED STATES PATENT OFFICE.

HARLEY F. WILSON AND WILLIAM A. HADFIELD, OF MADISON, WISCONSIN, AS
SIGNORS TO GENERAL LABORATORIES, OF MADISON, WISCONSIN, A CORPORATION
OF ARIZONA.

METHOD OF STERILIZING BEEHIVES AND THE LIKE.

No Drawing.

Application filed November 24, 1922. Serial No. 603,118.

To all whom it may concern:

Be it known that we, HARLEY F. WILSON and WILLIAM A. HADFIELD, citizens of the United States, residing at Madison, in the 5 county of Dane and State of Wisconsin, have invented a new and useful Improvement in Methods of Sterilizing Beehives and the like, of which the following is a specification.

10 This invention relates to the control and extirpation of contagious bee diseases, and, more particularly, to the disease known as "foul brood" in its various forms, and will be fully understood from the following description.

In combating the bee diseases above referred to, it is necessary to employ some means or agents sufficiently high in sterilizing power to destroy not only the living 20 bacilli and bacteria causing the disease, but also the extremely highly resistant spores of some of these bacilli, and particularly of those causing the very virulent form of foul-brood known as "American foul-brood." 25 The means employed must likewise be effective, in its most desirable form, to dissolve out from and cleanse the hive and hive parts of the organic matter and particularly the residue of dead larvæ which form the most 30 favorable medium for the development of the spores and the propagation of the various forms of bacteria responsible for the diseases. At the same time, they must be of such a nature that they will not leave the 35 hive and hive parts distasteful to or uninhabitable by the adult bees and thereby necessitate destruction of the hive or loss of the colony.

It has been found, in accordance with this 40 invention, that the hive and hive parts may be completely disinfected and sterilized against even the most virulent form of foul-brood by the application in a suitable manner of solutions of soluble hypochlorites and 45 particularly of sodium hypochlorite. For the treatment of the hive and hive parts, where a solvent action toward organic matter is not required, any suitable hypochlorite solution containing at least 1% of sodium 50 hypochlorite, and preferably about 3% may be employed, for example, by spraying or painting on the interior of the hive and on

the hive parts. Where a solvent action upon organic matter is desired, a solution is employed containing free alkali in addition 55 to the hypochlorite, the most suitable alkaline material being sodium carbonate. With increasing proportions of free alkali higher solvent action results, the preferred proportions being from one to three times the proportion of sodium hypochlorite.

In carrying out the present invention the hypochlorite solution is applied to the hive and all the hive parts. For the disinfection of these parts, where substantially no organic débris is present, the solution employed need not contain excess free alkali. Where organic matter is or may be present, particularly in the treatment of combs, frames and supers, it is preferred to employ a liquid in which free alkali is present, the preferred solution containing about 3% sodium hypochlorite and 8 to 9% sodium carbonate. This solution may likewise be employed where large amounts of organic 70 matter must be dissolved out, for example, in cleaning comb containing larvæ dead and dying from the disease and their decomposed remains. The solution quickly dissolves out this organic matter, the caps of the cells 75 having been previously removed, and destroys the bacteria and spores, completely sterilizing the comb and rendering it available for re-use.

It is clearly apparent that the specific nature of the hypochlorite solution employed may be varied with the character of the work to be done by it, and particularly with reference to the presence of organic débris. It is preferred, however, to employ solutions 80 having a higher alkalinity, as above described, as such solutions effect the rapid solution of any organic matter that may be present, even if unsuspected. The treatment effects a complete sterilization and 85 leaves no residue poisonous to the bees or harmful to them.

We claim as our invention:

1. The method of disinfecting honey-producing and handling devices, bee-hives and 100 hive parts which consists in applying thereto a solution of hypochlorites.
2. The method of disinfecting bee-hives and hive parts which consists in applying

thereto a solution of sodium hypochlorite containing free alkali.

3. The method of disinfecting bee-hives and hive parts which consists in applying thereto a solution of sodium hypochlorite containing sodium carbonate in the proportion of substantially one to three times the proportion of the sodium hypochlorite.

5 thereto a solution of sodium hypochlorite containing sodium carbonate.

4. The method of disinfecting beehives

and hive parts which consists in applying thereto a solution of sodium hypochlorite containing sodium carbonate in the proportion of substantially one to three times the proportion of the sodium hypochlorite.

HARLEY F. WILSON.

WILLIAM A. HADFIELD.
